UNITED STATES PATENT OFFICE.

JOHN D. WEBBER, OF BAYONNE, NEW JERSEY, ASSIGNOR TO INTERNATIONAL PAPER COMPANY, A CORPORATION OF NEW YORK.

MACHINE FOR MAKING TUBULAR CONTAINERS.

Application filed June 13, 1922. Serial No. 567,961.

To all whom it may concern:

Be it known that I, JOHN D. WEBBER, a citizen of the United States, residing at Bayonne, in the county of Hudson and State of New Jersey, have invented certain new and useful Improvements in Machines for Making Tubular Containers, of which the following is a specification, reference being had therein to the accompanying drawings.

10 This invention relates to machines for making tubular articles, such as paper cartons or receptacles, and the invention consists of certain improvements in the type of machine set forth in an application filed by 15 George W. Beadle on the 5th day of May 1920, Patent No. 1,444,096. In the machine of said application, a series of mandrels is mounted on a suitable carrier which is rotated step by step, so that the individual 20 mandrels will be presented in succession to blank extracting and feeding mechanisms, blank winding mechanisms, blank spinning mechanisms, bottom forming mechanisms, and an ejector mechanism for ejecting the 25 finished carton from the mandrels, the said several mechanisms being formed and co-ordinated in their operations to wind on each mandrel two blanks, one upon the other, and seat a bottom within the first wound blank and a second bottom against the first wound blank. In said machine the two blanks are extracted 30 and fed to the mandrels respectively from two blank holders situated at opposite ends 35 of the machine, and in their passage from the holders, the blanks are supplied with adhesive to cause the convolutions of the wound blanks to adhere to each other.

The object of my invention is to provide 40 means for holding or clamping the seams of the wound cemented blanks on the mandrels, so that the seams will have time to dry sufficiently to prevent loosening or separation of the seam surfaces during the operation of the machine in forming the cartons. With 45 this and other objects in view my invention consists of a presser or clamping member associated with each mandrel and operated to successively clamp or press the seam of the 50 blank after it is wound into a tube upon the mandrel.

The invention consists also of means associated with the presser device, to guide the

blank around the mandrel in the winding operation. 55

The invention consists also in the details of construction and combination of parts hereinafter described and claimed. The improved features constituting my invention will be described in the detailed specification 60 to follow, and the novel parts thereof will be pointed out in the appended claims.

In the accompanying drawings:

Fig. 1 is a side elevation of such parts of the machine of said application as will be 65 necessary for an understanding of my invention.

Fig. 2 is a view showing the carton in its different stages of formation.

Fig. 3 is a fragmentary view, in elevation, of the mandrels, their carrying spider, and the associated parts, with my invention embodied therein, certain of the parts being omitted. 70

Fig. 4 is a side elevation, on an enlarged 75 scale, of one of the forming mandrels having my improved seam clamping device applied thereto.

Fig. 5 is a horizontal sectional plan view 80 of the same on the line 5—5 of Fig. 4.

Fig. 6 is a front elevation of a mandrel and the associated seam clamping device, showing the first blank wound on the mandrel with its seam clamped by my said device. 85

Fig. 7 is a similar view showing the mandrel with the two blanks wound thereon and with both seams held by the clamping device.

Fig. 8 is a side elevation of the blank winding rollers, showing in dotted lines 90 the relation thereto of the blank guiding members.

Referring to the drawings:

Referring to Figs. 1 and 2, the tube or carton formed by the machine as set forth in said Beadle application, is made up from two blanks A and B which are wound one around the other on each of a series of forming mandrels C on a step by step movable mandrel-carrying spider D, with the convolutions of the wound blanks cemented together. In the formation of the carton, a blank A is first fed from a pile of the blanks at the left of the machine Fig. 1, to the mandrel at position No. 1, in which feed, 100 adhesive is applied to the rear half of the

blank by an adhesive applying surface E on a rotary drum F. As the advancing end of the blank reaches the mandrel at position No. 1 it is coiled around the mandrel by 5 opposing rotary winding rolls G, G, mounted permanently in the machine at this point, the effect of the winding operation being to coil or wind the blank around the mandrel in two convolutions cemented to each other 10 and forming a tube presenting a straight seam extending longitudinally from end to end. The blank thus wound is shown at 1 Fig. 2. The mandrel carrier now advances one step and presents the mandrel, with the 15 wound blank thereon, to position No. 2 Fig. 1, at which point the end of the blank overhanging the end of the mandrel is acted on by a spinning mechanism (not shown) which turns or folds the end of the blank 20 inwardly as shown at 2 Fig. 2. A third movement of the mandrel carrier moves the mandrel and blank to position No. 3 Fig. 1 to receive a blank B from a pile of blanks at the right of the machine. This blank is 25 fed to the mandrel and during the feeding action, adhesive is applied to the surface of the same throughout its extent by an adhesive applying surface E' on a rotary drum F', and as the advancing end of the blank 30 reaches the mandrel it is acted on by opposing rotary winding rolls G', G' mounted permanently in the machine at this point, the effect of the winding operation being to wind blank B around blank A in two coils, 35 while cementing the blanks and coils together, whereby a straight seam will be presented extending longitudinally from end to end of blank B. The form of the wound blanks at this stage of the operation is shown at 3 and 4 Fig. 2. The carrier now 40 makes its fourth movement and brings the mandrel to position No. 4, an idle one, and then it moves further to position No. 5 at which point a bottom H is by a suitable 45 mechanism (not shown) formed and seated within the end of wound blank B and against the folded end of blank A as shown at 5 Fig. 2. The sixth movement of the mandrel carrier moves the mandrel and 50 wound blanks to position No. 6 Fig. 1 at which point a second spinning mechanism (not shown) acts on the projecting end of wound blank B and folds or spins the same inwardly against bottom H to confine said bottom as shown at 6 Fig. 2. On the 55 seventh movement of the carrier the mandrel and blanks thereon are carried to position No. 7 Fig. 1 at which point a suitable mechanism (not shown) acts to form a second bottom I and seats the same within the inturned end of wound blank B as 60 shown at 7 Fig. 2 thereby completing the carton, which in the next and final movement of the carrier, is carried to position 65 No. 8 Fig. 1 where it is ejected from the

mandrel. It will be understood that each mandrel is carried through the above described operations in succession, so that there are a number of cartons in the machine at one time in different successive 70 stages of formation. The various mechanisms above referred to in general terms are fully set forth and described in said Beadle application before mentioned, to which reference may be had for a more detailed description than is here given, the above general description being sufficient for a full understanding of my present invention which will now be described. 75

As shown more particularly in Figs. 3 to 80 7 the presser or seam clamping device comprises opposing clamping jaws 10, 10, which are sustained by the mandrel carrier in operative relation to the respective mandrels, one set of jaws for each mandrel, and the 85 said jaws are movable to and from each other so that they may be opened to permit the blanks to be wound around the mandrel, and then closed on the wound blanks to 90 press down on and hold the seam while it dries. The jaws and associated parts are the same in form and construction for the several mandrels and therefore a description of one set will suffice.

The mandrels C consist each in the present instance of a tubular cylindrical shell having fixed within it at its opposite ends, two hubs or discs c—c' journaled on a rod 11, which several rods are fixed at their inner ends to the mandrel carrier near its outer edge. The mandrel is confined removably on its rod by means of a split collar c² seated in a peripheral groove in the outer end of the rod and held together by a spring clamp c³ fitting in an annular groove in the collar, whereby the mandrel may be removed endwise from the rod when desired. At its opposite end the mandrel is held in position by means of a collar c⁴ fixed to the rod. The mandrel carrier is fixed to a horizontal shaft 12 mounted rotatably in the machine and operated to advance the mandrels step by step, by a suitable operating mechanism such as is described in said application above referred to. Inward of 100 each rod 11, a horizontal stud 13 is fixed to the mandrel carrier and projects some distance on both sides of the same, and opposing clamp frames 14 and 15 are pivotally mounted on the projecting ends of the stud and have connected to them the two seam clamping jaws 10, 10 before alluded to, the relation of the parts being such that the jaws will be sustained on opposite sides of the mandrel. The clamp frame 14 consists of outer and inner parallel arms 14^a and 14^b mounted at their inner ends to rock on the stud 13, and a longitudinal connecting bar 14^c is connected to the outer ends of the arms. Likewise clamp frame 15 con- 105 110 115 120 125 130

sists of inner and outer parallel arms 15^a and 15^b mounted at their inner ends to rock on the stud, and a longitudinal connecting bar 15^c is fixed to the outer ends of the arms, 5 the arms of frame 15 being spaced some distance inward of the arms of frame 14 so as to leave spaces between said arms at the opposite ends of the stud. A coiled spring 16 surrounds the stud in the space between 10 the inner arms of the clamp frames and the coil of the spring is extended in opposite directions in the form of spring arms 17, 17, one of which is engaged with clamp frame 14, and the other with clamp frame 15, the said spring arms tending to 15 yieldingly hold the clamp frames apart and the jaws in open position as shown at the left in Fig. 3. The seam clamping jaws 10, 10 consist of elongated segmental shells or 20 casings 18 fixed to and extending forwardly respectively from the longitudinal bars of the two clamp frames, and the inner concave faces of the shells are lined with some soft yielding material such for instance as 25 sponge rubber which is cemented or otherwise fastened to the shells. The inner opposing clamping faces of the jaws are thus curved inwardly or concaved so as to follow the contour of the cylindrical mandrel, 30 and they extend throughout the length of the mandrel on opposite sides of the same, so that when the jaws are closed on the wound blanks on the mandrel, one jaw, that on the right in Fig. 6, will engage and press 35 on the seam of the wound blank A and the other jaw that on the left in Fig. 7 will engage and press on the seam of blank B.

Actuating means for the jaws are provided whereby they will be closed on the 40 mandrel after the blank A is wound thereon, so as to hold the seam of the blank, then opened partially to permit the winding of blank B, then closed again on blank B to hold its seam, and finally fully opened to 45 permit the finished carton to be ejected from the mandrel. These operations are automatically performed with respect to each set of jaws as their associated mandrels move successively from one position to 50 the other in the operation of the machine, and any suitable mechanism to effect these operations may be used. I prefer however to employ the mechanism shown more particularly in Figs. 3, 4 and 6 where it will 55 be seen that a radially movable slide plate 19 is located between the outer arms 14^a and 15^a of the clamp frames, and is formed with a longitudinal slot 19^a straddling the stud 13, the mandrel supporting rod 11, and 60 a guide roller 20 journaled on the outer side of a rod 21 depending from the outer edge of the mandrel carrier, the said slide plate being thus constrained and guided radially by the stud, roller and rod. At its upper 65 end the plate carries a horizontal pin 22

which projects on opposite sides of the plate and which in the radial sliding movements of the plate, engages the inner edges of the upper terminal portions of two rocking cam arms 23 and 24 fixed at their inner ends respectively to the outer arms 14^a and 15^a of the two clamp frames and extending on opposite sides of the slide plate. These fingers are urged inwardly towards each other so as to maintain engagement with the pin by the spring 16 in its action in holding the clamping jaws apart. The fingers are each formed on their inner edges with four cam surfaces 25, 26, 27 and 28 arranged one after the other in the length of the finger, and adapted to engage the pin on plate 19 as it is moved inwardly, and the construction, form and relation of the parts is such that when the pin engages the cam surfaces 26, the jaws will be separated sufficiently to permit the first blank to pass between them and the mandrel in the first winding operation as shown at position 1, Fig. 3. When the pin is engaged with the cam surfaces 25, the jaws will be fully closed on the mandrel as shown at position 2 Fig. 3. When the pin is engaged with the cam surfaces 27, the jaws will be separated slightly further than when controlled by the cam surfaces 26, so as to permit the winding of the second blank on the first wound blank; and when the pin is engaged with cam surfaces 28, the jaws will be permitted to be fully opened as shown at position 8 Fig. 3 to permit the carton to be ejected from the mandrel.

The operation of the slide plates to bring the different cam surfaces of the fingers into action, is effected in the present instance by the cam system shown more particularly in Fig. 3. This cam system comprises a semicircular frame or plate 29 fixed in position in the machine and disposed edgewise in the plane of the slide plates, the inner edge of the frame 29 being formed with three cam surfaces 30, 31 and 32 in position to be engaged by rollers 33 journaled on the sides of the slide plates at their outer extremities. These cam surfaces when engaged by the roller 33 will shift the slide plate to such positions as to successively engage the pin 22 with cam surfaces 26 and 25 respectively to first partially close the jaws at position 1 for the first winding, and then to wholly close the jaws at position 2 after the first winding, and to again wholly close the jaws at position 4 after the second winding. Associated with this semi-circular cam plate is a short fixed cam plate 34 located at position 3, the outer active edge 35 of which is in position to be engaged by the roller 33 as the mandrel approaches position 3, the action of the cam being to shift the slide plate outwardly and engage pin 22 with cam surfaces 27 and thereby open the

jaw slightly to admit the second blank B. A third fixed cam plate 36 is located at position 8 where the ejection of the finished carton takes place, and the outer active edge 37 of this cam is adapted to be engaged by the roller 33 as the mandrel approaches the ejecting position, and by such engagement the slide plate will be drawn outwardly to its full extent thereby engaging pin 23 with cam surfaces 28 of the fingers and permitting spring 16 to swing the jaws open to their full extent as shown.

The operation of the parts so far described is as follows.

With the mandrel at position No. 1, Fig. 3, and with the seam pressing jaws partially open, as determined by the engagement of pin 22 on slide plate 19 with cam surfaces 26 on cam arms 23, the blank A, supplied with adhesive, is fed to the mandrel and is wound around the same by the first set of winding rollers G, the completion of the winding operation bringing the seam of the tube within the area of one of the seam clamping jaws. The mandrel now advances to position No. 2, during which advance, roller 33 on slide plate 19 travelling on the cam surface 31 pushes the sliding plate inwardly and engages pin 22 with cam surfaces 25 which causes the seam clamping jaws to close on the wound blank and press on the seam and thereby hold it against separation. The mandrel next advances to position No. 3 to receive the second blank B, and in approaching said position, roller 33 rides along the cam edge of the short cam 34, whereby the slide plate will be pulled outwardly and will engage pin 22 with cam surfaces 27 and will thereby open the clamping jaws more widely than they were opened at position No. 1, in order to permit blank B to be wound around blank A. In this position of the mandrel, blank B, with the adhesive applied, is fed to the mandrel, and is wound thereon around the wound blank A by the second set of winding rollers G, the completion of the winding operation bringing the seam of the wound blank B within the area of the other seam clamping jaw. The mandrel with the two blanks wound thereon next advances to position No. 4, during which advance, roller 33 will ride on cam surface 32 and the slide plate will be pushed inwardly again and will engage pin 22 with cam surfaces 25, which action will close the jaws on the wound blanks on the mandrel, similar to the closing action at position 2, and the jaws will press firmly on and hold the two seams against separation. From this point on in the advance of the mandrel towards the ejecting position No. 8 pin 22 will remain engaged with cam surfaces 25, and the jaws will be maintained

in closed position so that the seams will be held down during the remaining portion of the period of advance, and the adhesive will have ample time to dry before the ejection of the finished carton takes place. In the final movement of the mandrel as it approaches the ejecting position, roller 33 will ride along the outer edge of cam 36, and by the time the mandrel reaches the ejecting position, pin 22 will have become engaged with cam surfaces 28, and the jaws will be opened to their full extent by spring 16. The ejecting mechanism now comes into action and ejects the finished carton from the mandrel. In the continued advance of the empty mandrel to position No. 1, roller 33 will engage cam 30 and by the time the mandrel reaches position No. 1, pin 22 will have engaged cam surfaces 26 again and the jaws will be again opened slightly to receive blank A as before.

It will be understood that there is a pair of seam clamping jaws associated with each mandrel, and that each set of jaws in the complete cycle of operation of its associated mandrel, goes through the different operations above described. In Fig. 3 the jaws and mandrels are shown by dotted lines in positions Nos. 5, 6 and 7, to better illustrate the other parts.

From the foregoing description of the construction and operation of the parts, it will be understood that the point on cam 30 at position No. 1 is such that when engaged by roller 33, the seam clamping jaws will be partially opened to receive the first blank, and that from this point the cam surface extends at a gradual inward inclination and finally merges into cam surface 31 at position No. 2, which when engaged by the roller will fully close the jaws on the wound blank. The short cam 34 at position No. 3 extends gradually outwardly so as to engage the opposite side of the roller, and reaches such point at position No. 3 that the jaws will be opened slightly wider and the opening movement effected by cam 30, in order to admit the second blank. Cam surface 32 extends gradually inwardly similar to cam 31, and reaches its highest point at position No. 4 and pushes the sliding plate inwardly and closes the jaws on the two wound blanks. Cam 36 extends in a more abrupt outward curve and reaches its highest point at ejecting position No. 8 and acts on the inner side of the roller and pulls pin 22 outwardly to its full limit and thereby permits the jaws to be opened to their widest extent. The effect of the several cams is therefore to first open the jaws slightly to receive the first blank, then to close the same on the first wound blank to act with sustained pressure on the blank, then to open them more widely to receive the second blank, then to close the same on the two wound blanks to act with

sustained pressure on the seams of the two wound blanks, and finally to open the jaws to the fullest extent to permit the ejection of the finished carton.

- 5 In order that when the clamping jaws are partially opened as at position No. 1 to receive blank A and at position No. 3 to receive blank B, the sheet or blank will be properly guided around the mandrel in the 10 winding operation effected by the rollers G, each jaw has attached to it a number of transversely extending blank guiding members, in the present instance in the form of spring bows 40. These bows are arranged 15 at intervals in the length of the jaw, and while following the concaved contour of the active face of the jaw, they stand out or are spaced therefrom, so that when the jaws are partially opened as at position No. 1, the 20 spring bows on the opposing jaws will bear with a gentle yielding pressure against the opposite sides of the mandrel, and the blank will be caused as it is fed by the rollers G in the winding operation, to pass between the 25 spring bows and the surface of the mandrel and be thus caused to adhere snugly to the mandrel and follow closely the contour of the same notwithstanding the partially 30 opened condition of the jaws. When the jaws are closed on the wound blank as the mandrel approaches position No. 2 the spring bows will yield as the jaws move inwardly towards each other, and the bows will become embedded in the soft rubber 35 lining of the jaws as the latter is forced into intimate contact with the wound mandrel in holding the seam closed. The same action takes place at position No. 3, except that the spring bows in that position of the mandrel 40 press upon the wound blank A on the mandrel and they act to guide the second blank snugly and closely around the first in the second winding operation.
- In the present instance the bows are each 45 formed from a spring metal strip which is fastened at its ends to the outer side of the jaw casing as at 41, and extends in opposite directions from its points of attachment, to points beyond the opposite edges of the jaws, 50 where the strip is bent back on itself as at 42 and is curved as at 43 to follow the contour of the inner face of the jaw and in spaced relation to the curved surface of the rubber lining of the jaw. The curved portions 55 of the bows extend at an inclination across the face of the jaw, as best shown by dotted lines in Fig. 4, so that the opposite ends of the loops are out of transverse alignment with each other, or in other words they 60 break joint. The result is that the ends of the bows at the adjacent edges of the opposing jaws, will stand opposite to each other, while the other ends of the bows will stand opposite to each other, but will be disposed 65 opposite the spaces between the first men-

tioned ends, as shown in Fig. 5. The purpose of this arrangement is to permit the bows at their ends to extend between the spaces 44 between the active surface 45 of the winding rolls G, which rolls as shown in 70 Fig. 8, are so disposed that these active surfaces will be offset relatively to each other to jointly engage the blank throughout its extent in the winding operation. Reinforcing springs 46 are attached to the jaw casing and bear against the outer sides of the 75 spring bows to reenforce their spring action.

In order, in the winding operation, to prevent the corners of the blank or sheet from catching against the abrupt faces of the rubber lining of the jaws, each jaw is provided at its opposite ends with guides 47, see Figs. 4 and 5, which guides in the present instance are each in the form of a metal strip attached to the rear face of the 80 jaw and extending beyond the edge of the same where it is bent inwardly on itself so as to present an inclined surface 47^a at the end of the rubber lining. These inclined surfaces will act, as the corners of 85 the sheet approach the edges of the rubber lining to guide the same without obstruction between the mandrel and lining.

Due to the form and arrangement of the 90 spring bows 40, the sheet or blank may be wound in either direction about the mandrel, the first blank winding in an anti-clockwise direction, while the second blank is wound in a clockwise direction.

In the foregoing description and accompanying drawings I have set forth my invention in the particular detailed form and construction of the parts which I prefer to adopt. It will be manifest however that these details may be variously changed 95 and modified without departing from the spirit of the invention; and further it will be manifest that these details are not limited to any particular form or construction of the parts except in so far as such limitations 100 are specified in the claims.

Having thus described my invention, what I claim is:

1. In a machine of the type described, the combination of a forming mandrel movable to different positions in the machine to receive separate blanks therearound in succession to form superposed tubes, a seam pressing member associated with the mandrel and movable with it, means for operating said member after the application of the first blank to the mandrel to press upon the seam of said blank, and means for again operating said member after the application of the second blank to the mandrel to press upon the seam of said second blank.

2. In a machine of the type described, the combination of means for forming two blanks into tubes one around the other with

- the seams disposed out of coincidence with each other to produce a carton, and seam clamping jaws operable to press upon the seams of the two tubes in succession.
5. 3. In a machine of the type described, the combination of a mandrel adapted to be supported in position to have a blank applied therearound to form a tube and movable to advance the tube to receive a second blank around the first to form a second tube superposed on the first, seam clamping jaws movable with the mandrel, means to hold the jaws open in the first receiving position of the mandrel, means for closing the jaws on the first tube to press on the seam thereof, means for opening the jaws in the second receiving position of the mandrel, and means for closing the jaws on the second tube to clamp both seams.
10. 4. In a machine of the type described, the combination of a forming mandrel movable from a first blank receiving position to a second blank receiving position and finally to an ejecting position, means for winding two blanks thereon in succession to form superposed tubes, a seam pressing member associated with the mandrel and movable with it, means for operating said member to press with a sustained pressure upon the seam of the first tube, means for operating said member to relieve the pressure when the mandrel is at the second receiving position, means for operating the member to press with a sustained pressure upon the seam of the second tube received by the mandrel at second position, and means for operating the member to disengage the tubes at ejecting position.
15. 5. In a machine of the type described, the combination of a forming mandrel movable to different positions in the machine, a seam pressing member associated with the mandrel and movable with it, and fixed cams in position to operate said member at different periods in the movement of the mandrel.
20. 6. In a machine of the type described, the combination of a series of forming mandrels movable to different positions in the machine about a common axis, a seam pressing member associated with each mandrel and movable with it, and fixed cams surrounding said common axis in position to operate said members at different periods in the movement of the mandrels.
25. 7. In a machine of the type described, the combination of a forming mandrel, a carrier for the same, seam clamping jaws movably sustained by the carrier in position to open and close on the mandrel, a jaw actuating member movably sustained by and movable with the carrier and operatively engaged with the jaws for opening and closing the same, and means for operating said actuating member.
30. 8. In a machine of the type described, the

combination of a forming mandrel, a carrier for the same, seam clamping jaws movably sustained by the carrier to open and close on the mandrel, a jaw actuating member sustained by the carrier and movable transversely of the axis of the mandrel and operatively engaged with the jaws for opening and closing the same, and means for operating said actuating member.

9. In a machine of the type described, the combination of a forming mandrel, a movable carrier for the same, seam clamping jaws movably sustained by the carrier to open and close on the mandrel, a jaw actuating member movable with the carrier and movable also relatively to the same to actuate the jaws, and fixed cams in the path of movement of the jaw actuating member to operate it.

10. In a machine of the type described, the combination of a forming mandrel, a carrier for the same, seam clamping jaws movably sustained by the carrier to open and close on the mandrel, means for positively opening the jaws and maintaining them in open position to permit the application of the blank to the mandrel to form a tube, and means for thereafter closing the jaws and maintaining them in closed position to apply sustained pressure to the seam of the tube.

11. In a machine of the type described, the combination of a forming mandrel, a carrier for the same, seam clamping jaws pivoted to the carrier in position to open and close on the mandrel, arms on the respective jaws, a jaw actuating member sustained by the carrier in position to engage said arms and actuate the jaws, and means for operating the actuating member.

12. In a machine of the type described, the combination of a forming mandrel, a carrier for the same, seam clamping jaws pivoted to the carrier to open and close on the mandrel, arms connected with the jaws and provided with cam surfaces, a jaw actuating member sustained by the carrier and provided with a pin, said actuating member being movable to engage the pin with the different cam surfaces, and means for operating the actuating member.

13. In a machine of the type described, the combination of a forming mandrel adapted to have a blank wound therearound to form a tube, a presser member to act on the seam of the tube, and yielding blank guiding means carried by the presser member and adapted to bear on the forming mandrel.

14. In a machine of the type described, the combination of a forming mandrel adapted to have a blank wound therearound to form a tube, a seam presser member normally disengaged from the mandrel to permit the blank to be applied, and

movable to press upon the seam of the tube, and blank guiding members yieldingly sustained by the presser member and adapted when the latter is disengaged from the mandrel, to press upon the same and guide the blank therearound.

15. In a machine of the type described, the combination of a forming mandrel adapted to have a blank wound therearound to form a tube, clamping jaws normally disengaged from the mandrel to permit the blank to be applied and movable to press upon the seam of the tube, and blank guiding means yieldingly sustained by the jaws and extending across the face thereof in spaced relation thereto, said guiding members adapted to bear gently on the mandrel when the jaws are disengaged therefrom.

20 16. In a machine of the type described, the combination of a forming mandrel adapted to have a blank wound therearound to form a tube, seam clamping jaws provided with a lining of yielding material, said jaws being movable into engagement with the tube to press on the seam thereof, and yielding blank guiding strips sustained by the jaws and extending across the face of the lining and spaced therefrom, said strips adapted to bear with a gentle pressure on the mandrel to guide the blank.

17. In a machine of the type described, the combination of a forming mandrel adapted to have a blank wound therearound to form a tube, seam clamping jaws movable to close and press upon the seam of the tube, and spring bows sustained by the jaws and extending across the face thereof in spaced relations to the same, said bows adapted to bear upon the mandrel to guide the blank.

18. In a machine of the type described, the combination of a mandrel, blank winding rollers rotatable at opposite sides of

the same to wind the blank therearound to form a tube, and seam pressing members disposed in the spaces between the winding rollers and movable inwardly towards each other to press upon the seam of the tube.

19. In a machine of the type described, the combination of a mandrel, rotary blank winding rollers between which the mandrel is positioned to receive a blank, said rolls being operable to wind the blank around the mandrel to form a tube, said mandrel being movable from its receiving position to advance the tube, and seam pressing jaws movable with the mandrel and operable to press upon the seam of the tube in the spaces between the winding rollers.

20. In a machine of the type described, the combination of a forming mandrel movable from a first blank receiving position to a second blank receiving position and finally to a carton ejecting position, means for winding two blanks on the mandrel in succession to form superposed tubes to constitute a carton, seam pressing jaws associated with the mandrel and movable with it, means for opening the jaws at the first blank receiving position of the mandrel, so that the blank may be wound thereon to form a tube, means for closing the jaws on said tube to press on the seam thereof, means for opening said jaws wider than the first opening when the mandrel arrives at its second blank receiving position so that a second blank may be wound thereon to form a second tube superposed on the first, means for closing the jaws on the superposed tubes to press upon the seam of the second tube, and means for widely opening said jaws when the mandrel arrives at the carton ejecting position to enable the carton to be ejected therefrom.

In testimony whereof, I have affixed my signature hereto.

JOHN D. WEBBER.
